Patented June 11, 1963

195,420

COMBINED ELECTRIC CAN OPENER AND KNIFE SHARPENER

Henry J. Talge, Kansas City, Mo., and Downer P. Dykes,
Lawrence, Kans., assignors to John C. Hockery, trustee,
Kansas City, Kans.

Filed Nov. 16, 1962, Ser. No. 72,514

Term of patent 14 years

(Cl. D37—1)

Fig. 1.

Fig. 2.

*Fig. 3.**Fig. 4.*

FIG. 1 is a front elevational view of a combined electric can opener and knife sharpener embodying our new design;

FIG. 2 is a side elevational view of same taken from the left-hand side of FIG. 1;

FIG. 3 is a top plan view of same; and

FIG. 4 is a rear perspective view of same showing the right side thereof as viewed in FIG. 1.

We claim:

The ornamental design for a combined electric can opener and knife sharpener, as shown.
